CLAIM

The ornamental design for a combination nail clipper and cover therefor, as shown and described.

DESCRIPTION

FIG. 1 is a perspective view of a combination nail clipper and cover therefor showing my new design;

FIG. 2 is a top view thereof;

FIG. 3 is a bottom view thereof;

FIG. 4 is a front view thereof;

FIG. 5 is a rear side view thereof;

FIG. 6 is a left side view thereof;

FIG. 7 is a right side view thereof;

FIG. 8 is a top view of the nail clipper of FIG. 1 with the cover removed for completeness of the disclosure;

FIG. 9 is a bottom view of the nail clipper of FIG. 8;

FIG. 10 is a front view of the nail clipper of FIG. 8;

FIG. 11 is a rear view of the nail clipper of FIG. 8;

FIG. 12 is a left side view of the nail clipper of FIG. 8; and,

FIG. 13 is a right side view of the nail clipper of FIG. 8.
